UNITED STATES PATENT OFFICE.

HENRY HORNBECK, OF ELIZABETH, NEW JERSEY.

PIANO-FRAME.

SPECIFICATION forming part of Letters Patent No. 794,356, dated July 11, 1905.

Application filed November 23, 1904. Serial No. 233,959.

To all whom it may concern:

Be it known that I, HENRY HORNBECK, a citizen of the United States, and a resident of Elizabeth, Union county, State of New Jersey, have invented certain new and useful Improvements in Piano-Frames, of which the following is a specification.

My invention relates to stringed musical instruments, such as pianos, and has for its object to provide a frame construction which will firmly hold the pressure-bar engaging the strings without requiring expensive work in fitting the parts together.

The invention will be fully described hereinafter, and the features of novelty pointed out in the appended claims.

Reference is to be had to the accompanying drawings, in which—

Figure 1 is a front view of a portion of a piano-frame with my invention applied thereto. Fig. 2 is an enlarged sectional view taken on line 2 2 of Fig. 1, and Fig. 3 is a sectional view illustrating another form of my invention.

My invention is applicable to piano-frames of various constructions.

In the drawings the strings A are secured at their upper ends to wrest-pins B, arranged at the upper portion C of the frame. The lower ends of the strings are secured at D to the lower portion C' of the frame.

J indicates the back of the piano, E the sounding-board, and F the sounding-board bridge, projecting through an opening C² of the frame, which carries the agraffes F' for guiding the strings and determining the length of their vibrating portions.

My invention has especial reference to the manner of securing the pressure-bar G, which engages the strings from the front and holds them against the ridge C³, which determines the upper ends of the vibrating portions of the strings. As shown in Figs. 1 and 2, on the front face of the upper frame portion C, I arrange holding members H H', generally in the nature of ribs. Each member H aligns with one of the members H', but is spaced therefrom, the adjacent end surfaces of such members being beveled, so as to converge toward the front—that is, toward the exposed

surfaces of said holding members. The wedge-shaped opening thus formed between the spaced ends of the holding members H H' should be larger than the cross-section of the pressure-bar G, which is also wedge-shaped, 55 at least where it fits between such holding members. It will be understood that the pressure-bar is not intended to engage the holding members, and the space left between said holding members and the pressure-bar is 60 filled with a suitable material I, such as lead, Babbitt metal, cement, or composition, which is sufficiently plastic to be properly introduced into and to fill the said space. Such material will conform to any irregularities of the surfaces which it engages and will thus take a very firm hold both on the pressure-bar G and on the holding members H H'. With this construction I avoid the necessity for carefully smoothing and finishing the adjacent ends of 70 the holding members and the corresponding portions of the pressure-bar. In fact, the construction is more effective if these surfaces are left rough and unfinished, since the plastic filling I will then have a better hold. 75 Of course the material of this filling should be strong enough to resist the forward pressure of the strings on the pressure-bar. When the said bar is inserted from the front, as in the drawings, the widest portion of the pressure-bar should of course be narrower than the narrowest portion of the opening between adjacent ends of the holding members H H'. The ends of the pressure-bar are preferably 80 not exposed, but embedded in the filling I, 85 and, as shown at the right-hand end, a continuous holding member H² may be employed at the end instead of a set of alining members H H'.

It will be seen that the herein-described 90 manner of securing the pressure-bar is efficient and inexpensive. It also materially facilitates removal of the pressure-bar in case of need without injury either to said bar or to the holding members.

In the form of my invention shown in Fig. 3 the holding members have their adjacent end surfaces beveled, so as to diverge from the rear to the front, instead of from the front to the rear, as in Fig. 2, the said 100

space between the holding members being filled with any suitable material in the same manner as described with relation to Figs. 1 and 2. A bolt α passes through the upper portion C of the frame and through the said filling and into the pressure-bar G as an additional means for securing said pressure-bar in place.

Various modifications may be made without departing from the nature of my invention.

I claim—

1. A frame for stringed musical instruments, comprising a frame proper having alined holding members the ends of which are spaced and beveled to form a wedge-shaped opening, a pressure-bar arranged to project into said opening and tapered within said opening in the same direction as the opening, and a retaining-filling between said pressure-bar and holding members.

2. A frame for stringed musical instruments, comprising a frame proper having holding members the ends of which are spaced from each other, a pressure-bar arranged to extend between said ends, and a retaining-filling between said pressure-bar and holding members.

3. A frame for stringed musical instruments, comprising a frame proper having holding members the ends of which are spaced from each other to form an opening, a pres-

sure-bar arranged to extend within said opening, but of materially smaller cross-section within the opening than the opening, so as not to fill the same entirely, and a retaining-filling to take up that portion of the opening which is not occupied by the pressure-bar.

4. A frame for stringed musical instruments, comprising a frame proper having alined holding members the ends of which are spaced and beveled to form a wedge-shaped opening, a pressure-bar arranged to project into said opening and tapered within said opening in the same direction as the opening, the widest portion of the bar within said opening being narrower than the narrowest portion of the opening, and a retaining-filling to take up that portion of the opening which is not occupied by the pressure-bar.

5. A frame for musical instruments, having holding members, a pressure-bar extending adjacent to said holding members but spaced therefrom, and a filling located in the spaces between the holding members and the adjacent portions of the pressure-bar.

In testimony whereof I have hereunto set my hand in the presence of two subscribing witnesses.

HENRY HORNBECK.

Witnesses:

JOHN LOTKA,

JOHN A. KEHLENBECK.
